POCKET CLIP FOR WRITING INSTRUMENT

Toshihiro Nakata, Tokyo, Japan, assignor to Platinum
Fountain-Pen Co., Ltd., Tokyo, Japan

Filed Dec. 3, 1971, Ser. No. 204,790

Claims priority, application Japan June 5, 1971;
July 22, 1971

Term of patent 14 years

Int. Cl. D19—99

U.S. Cl. D74—17 A

FIG. 2

FIG. 1

FIG. 4

FIG. 3

FIG. 6

FIG. 5

FIG. 1 is a left-side elevational view of a pocket clip for writing instrument showing my new design according to a first embodiment thereof;

FIG. 2 is a front elevational view of the clip shown in FIG. 1;

FIG. 3 is a front perspective view of the clip of FIG. 1;

FIG. 4 is a rear perspective view of the clip of FIG. 1;

FIG. 5 is a front perspective view of a pocket clip for writing instrument showing my new design according to a second embodiment thereof; and

FIG. 6 is a rear perspective view of the clip shown in FIG. 5.

I claim:

The ornamental design for a pocket clip for writing instrument, as shown and described.
